UNITED STATES PATENT OFFICE.

WILLIAM VOGLER, OF SOMERVILLE, MASSACHUSETTS.

ELECTRIC CONDUCTOR.

SPECIFICATION forming part of Letters Patent No. 460,606, dated October 6, 1891.

Application filed November 9, 1889. Serial No. 329,762. (No model.)

To all whom it may concern:

Be it known that I, WILLIAM VOGLER, of Somerville, county of Middlesex, State of Massachusetts, have invented an Improvement 5 in Electric Conductors, of which the following description, in connection with the accompanying drawings, is a specification, like letters on the drawings representing like parts.

This invention has for its object to provide 10 a novel electric conductor especially adapted to be used in telephonic communication.

In accordance with my invention a re-enforcing strip is interposed between two branches or wires, each of which has an independent semi-cylindrical insulation, the branches being on opposite sides of and the flat sides of the insulation resting upon the strip, an outer covering of insulation covering 15 the branches and re-enforcing strip.

20 My invention therefore consists, essentially, in an electric conductor consisting of two branches or wires, an independent semi-cylindrical insulation for each branch, and a re-enforcing strip interposed between said 25 branches, and upon the opposite sides of which the flat surface of the insulation rests, and an outer covering of insulation enveloping said branches and re-enforcing strip to secure the parts in place, substantially as will be de- 30 scribed.

Figure 1 represents a sufficient portion of 35 an electric conductor constructed in accordance with my invention to enable it to be understood; and Fig. 2, a transverse section on line $x x$, Fig. 1.

My improved electric conductor is composed of two wires or conductors $a a'$, forming branches of a metallic circuit, and a re-enforcing strip, web, or ribbon b interposed between 40 the said wires. The re-enforcing strip or ribbon b is made flat, so that an increased surface is obtained, against which the semi-cylindrical independent insulation b' , covering each 45 of the wires $a a'$, may bear, to thereby keep the said wires in their proper place on opposite sides of the re-enforcing strip. Each wire $a a'$, which may be an ordinary insulated wire, will be first covered with the semi-cylindrical insulation b' , and the flat side thereof will be 50 laid against the flat surface of the re-enforcing strip on each side, and the said wires will

then be secured in place by means of a covering c , preferably of cotton or other textile braid, saturated with insulating material enveloping said branches or wires, and the re- 55 enforcing strip to secure the parts in place.

The re-enforcing strip will preferably be made of metal, which may be steel, brass, &c., and the conductor used in telephonic communication, and when thus used the branches or 60 wires $a a'$ may be connected at their opposite ends to the re-enforcing strip and the latter form a common return for the said wires. In this manner each branch may form part of an independent metallic circuit, and induction 65 from one circuit to the other, or from extraneous sources, is obviated or reduced to a minimum. So, also, if desired, the branches or wires $a a'$ may be connected together to form a metallic circuit, and the re-enforcing 70 strip connected at its opposite ends to the ground to form an independent ground-circuit, by which currents induced from extraneous sources may be conducted to the ground. In either case a complete metallic circuit is 75 formed in a single conductor enveloped by a covering of insulation and requiring but a single insulator to support it.

The re-enforcing strip is preferably made of metal to enable my improved conductor to 80 be used in telephonic communication, as described; but I do not desire to limit my invention to the use of a metal strip, as the same may be made of other material—such, for instance, as wood, card-board, webbing, &c.—to 85 impart to the conductor the desired stiffness, and when so constructed the said conductor may be used for electric lighting and like uses. The flat re-enforcing strip prevents the tie-wires, by which the conductor is secured to 90 its insulator or support, from cutting into or abrading the insulation on the branch wires.

The re-enforcing strip, when made of metal, will be sufficiently thin to permit the conductor to be readily bent, and the flat sides 95 will be of sufficient width to prevent relative displacement of the insulation.

I claim—

As an improved article of manufacture, an electric conductor consisting of two branches 100 or wires, an independent semi-cylindrical insulation b' for each branch, and a re-enfore-

ing strip interposed between said branches, upon the opposite sides of which the flat surface of the insulation rests, and an outer covering of insulation enveloping said branches, 5 and re-enforcing strip to secure the parts in place, substantially as described.

In testimony whereof I have signed my

name to this specification in the presence of two subscribing witnesses.

WILLIAM VOGLER.
